(57) **CLAIM**

The ornamental design for a construction drilling cup, as shown.

DESCRIPTION

FIG. 1 is a bottom view of a construction drilling cup showing my new design;

FIG. 2 is a top view thereof;

FIG. 3 is a side view thereof;

FIG. 4 is a front view thereof;

FIG. 5 is a back view thereof;

FIG. 6 is a perspective view thereof; and,

FIG. 7 is a perspective view thereof.

1 Claim, 7 Drawing Sheets---
